UNITED STATES PATENT OFFICE.

MENZO M. BENSTER, OF GETTYSBURG, SOUTH DAKOTA.

WINDOW-BEAD FASTENER.

1,177,374.

Specification of Letters Patent. Patented Mar. 28, 1916.

Original application filed February 16, 1915, Serial No. 8,485. Divided and this application filed July 23, 1915. Serial No. 41,489.

To all whom it may concern:

Be it known that I, MENZO M. BENSTER, a citizen of the United States, and a resident of Gettysburg, in the county of Potter and 5 State of South Dakota, have invented new and useful Improvements in Window-Bead Fasteners, of which the following is a specification.

My invention relates to improvements in 10 windows and more particularly to window beads and fasteners, the present application being a division of my application for patent for windows, Serial No. 8,485, filed February 16, 1915, and has for its object to provide improved means for permitting the 15 ready removal of window sashes and for holding them in place in operable position.

My invention consists in certain features 20 of construction, arrangement, and combination of window beads and their fastening means as will be hereinafter described and pointed out in the claims, reference being had to the accompanying drawings forming part of the application, in which—

25 Figure 1 is a horizontal sectional view through a portion of window frame showing my improved bead fastening means. Fig. 2 is a perspective view of the bead removed from the window frame. Fig. 3 is 30 a perspective view of a sash runner used in connection with my bead. Fig. 4 is an enlarged sectional view of the spring actuated locking pin.

In carrying out my invention in connection with a frame and sash as indicated by 35 A and K a guide strap E is also used which lies against the inner side of the frame abutting at one end the rib k of the sash as clearly shown in Fig. 1; said guide strip

40 E is provided with slots e adjacent its upper and lower ends to receive the headed spring bolts F fitted in the tubes F³ secured in the frame near its upper and lower ends, a coiled spring F⁵ surrounding the shank of each 45 bolt and bearing at one end against shoulder f¹ on the bolt and at the opposite end against the inner end f² of the tube; the shank f³ of the bolt which is reduced is threaded at its free end where it passes through the inner 50 end of the tube and a nut f⁴ is threaded thereon whereby the amount of the part of the bolt projecting from the tube may be regulated according to varying thickness of beads and runner strips; an angled shelf 55 f⁵ is secured to the inner face of the frame

adjacent the tube and the nut f⁴ and forms a guide for the nut and also a lock for the same.

When the strip E is put in place in the window as shown in Fig. 1 and the bead placed in its proper relation thereto the openings e are in alinement with the openings f so that the bolt heads F⁶ may pass through both members E and F², the head being of such size that it just passes through 60 openings F in the plate F¹ secured to the bead F²; the head of each bolt is beveled on its rear face so that when the latch F⁴ frictionally mounted on plate F¹ is swung upwardly and to the left, the cut out or slot 65 f⁶ will pass over the bolt and engage the said rear face with a wedging action drawing the parts tightly together so as to exclude all wind and dust; or the latch itself 70 may be beveled.

It will be seen that the sashes can be readily and quickly removed by simply releasing the latch first, removing the bead and then taking out the strip E whereupon the lower or inner sash can be easily taken out 80 of the frame and into the room, the upper sash can then be removed by removing a parting strip D between the two sashes.

I claim:

1. In a window construction, the combination of a spring actuated headed bolt mounted in a side beam of the frame at the inside thereof, of a window bead having an opening to pass over said headed bolt, a latch pivoted at one end to said bead adjacent the opening and having a slot in one edge adapted to pass beneath the head of said spring actuated bolt to fasten the bead in place.

2. A window bead and fastener consisting 95 of a bead having an opening therethrough, a spring actuated headed bolt adapted to pass through said opening, the rear face of the bolt head being beveled, and a latch pivotally mounted on said bead adjacent the 100 aforesaid opening, said latch having a notch in one side edge adapted to pass on each side of the bolt and permit the latch to engage the beveled rear face of the bolt head with a wedging action to hold the bead tightly to 105 its place.

3. In a window bead fastener for window frames, the combination with a bead having an opening therethrough, a spring actuated headed bolt carried in the casing and 110

adapted to pass through said opening, and means for regulating that part of the bolt projecting through the aforesaid opening in the bead.

- 5 4. In a window bead fastening for window frames, the combination with a bead having an opening therethrough, a tubular socket fitted in the casing, a spring actuated bolt slidably mounted in said socket headed 10 at one end and adapted to project through

the opening in the bead and threaded at the inner end and projecting through the tubular socket into the window casing, and a nut engaging said threaded end, a latch pivotally mounted on the bead adjacent the 15 opening, said latch having a notch in one edge adapted to engage the bolt beneath its head.

MENZO M. BENSTER.
